UNITED STATES PATENT OFFICE.

JAMES EDWARD HARRISON, OF NEW YORK, N. Y.

MUFFLER OR PROTECTOR.

No. 891,166.

Specification of Letters Patent.

Patented June 16, 1908.

Application filed October 26, 1907. Serial No. 399,324.

To all whom it may concern:

Be it known that I, JAMES EDWARD HARRISON, a citizen of the United States, residing at New York, in the county of New York and 5 State of New York, have invented new and useful Improvements in Mufflers or Protectors, of which the following is a specification.

This invention relates to certain novel features of construction set forth in the following specification and claims and illustrated in 10 the annexed drawing in which:—

Figure 1 is a face view of a muffler embodying this invention. Fig. 2 is a section along line $x-x$ of the same. Fig. 3 is a section 15 along line $y-y$ of the same. Fig. 4 is a cross-section on the line 4—4, Fig. 1.

This muffler is essentially used by chauffeurs and such persons who are exposed to severe weather. The muffler is provided with 20 pockets which serve as receptacles for a number of articles such as veiling or handkerchiefs and a pair of ear muffs.

In this drawing the letter a designates a neck muffler which has tabs b at its neck portion with snap buttons whereby the muffler when in use can be looped and attached to the hanger of a coat. The muffler is also provided with a series of safety pins c so that 25 the flap portions thereof can be attached to the inner portion of said coat. The inner edges of the flaps of the muffler are slitted from near the bottom to within a short distance of the neck portion thus forming openings or mouths to pockets d in the muffler. 30 The slits or openings are adapted to be closed by means of snap buttons e "like glove fasteners". The pockets are adapted to contain veiling or handkerchiefs and a pair of ear muffs f which are fastened to the interior 35 of the pockets. When the muffs f are in use they can be drawn out of the pockets and being attached to the pockets by means of elasties can be stretched to the proper position on the ears.

40 The handkerchiefs or veils can be secured to the interior of the pockets by means of small safety pins or fastenings g so that when they get soiled they can be removed from the pockets and cleaned. In Fig. 1 the dotted 45 lines show the protectors drawn out of their

pockets and in this position they serve to protect and cover the chest and neck.

When the muffler is worn by a female the 55 pockets will contain veils and when they are drawn out of the pockets utilized to cover and protect the face and neck. A pair of goggles can also be placed in the pockets. Both of the tabs b are sewed or fastened to the neck portion of the muffler and each tab has a free end, one of the tabs having a 60 socket member, and the other a stud member, the free ends of the tabs being looped around the hanger of the coat and secured by snapping the stud member into the socket member. 65

What I claim is:—

1. A muffler or protector comprising a neck portion and flap members provided with pockets and having handkerchiefs adapted to form supplemental protectors 70 secured in the pockets.

2. A muffler or protector comprising a neck portion and flap members provided with pockets and having handkerchiefs adapted to form supplemental protectors 75 secured in the pockets, said pockets having their mouth portions provided with closing means.

3. A muffler or protector comprising a neck portion and flap members provided 80 with pockets and having handkerchiefs adapted to form supplemental protectors secured in the pockets, at the inner edges to allow the remaining portion of the handkerchief to be drawn out to serve as a veil or 85 covering for part of the wearer.

4. A muffler or protector comprising a neck portion and flap members provided with pockets and having handkerchiefs adapted to form supplemental protectors 90 secured in the pockets said muffler having tabs with attaching device adapted to engage the hanger or other part of an outer-garment.

5. A muffler or protector comprising a 95 neck portion and flap members provided with pockets and having handkerchiefs adapted to form supplemental protectors secured in the pockets and means for securing the flap portions to a garment. 100

6. A muffler or protector comprising a
neck portion and flap members provided
with pockets and having handkerchiefs
adapted to form supplemental protectors
5 secured to the pockets said pockets each
having their mouths facing each other and
closing means for the pocket mouths.

In testimony whereof I have hereunto set
my hand in the presence of two subscrib-
ing witnesses.

JAMES EDWARD HARRISON.
